ROTARY CUTTER

Application filed June 4, 1932. Serial No. 615,384.

This invention relates to rotary ground working implements and particularly to one used to chop up asparagus roots such as is shown in the co-pending application of Tony 5 S. Miller and ourselves, Serial No. 611,840, filed May 17, 1932.

In order to insure the efficient cutting action of the blades through the roots with a minimum of power we found it desirable 10 to set the cutting edges of the blades so that they are disposed in transverse acute angles to the line of travel or so that they have a shearing action when moving through the ground with the rotation of the rotary implement unit. We found however that if 15 the blades were mounted so that they extended in a transverse horizontal plane or parallel to the axis of rotation, that the cutting edges of the blades at that end which are naturally advanced relative to the other end 20 on account of the transverse acute angle at which such edges are disposed, wore more rapidly than at the other end and frequent resharpening was necessitated.

25 This is because the blades are mounted in connection with their supports so that they are disposed at an outward acute angle to a tangent, in order that the blades will enter the ground with a chisel-like effect and thus 30 relieve the drag on the back sides of the blades and their supporting pads. The advanced ends of the blades under the above mounting conditions therefore were positioned so that they engaged the ground 35 through a longer circular path than the opposite end, which obviously resulted in a faster wearing of the advanced end of the blade owing to the abrasive action of the dirt thereon.

40 The principal object of the present invention is to avoid this uneven wearing of the blades by mounting the same in such a manner that while the tangential angle of the blades to the axis of rotation and the setting 45 of the cutting edge of the blade at an acute angle to the line of travel is maintained, said cutting edge is disposed so that both ends, as well as all points in its length, are disposed the same distance from the axis of 50 rotation, or so that the cutting edge of the

blade as a whole is parallel to said axis. The cutting edge of the blade at all points in its length therefore is engaged with the ground for the same distance with the rotation of the implement and wear of the cutting edge 55 of the blade is even throughout its length.

A further object of the invention is to produce a simple and inexpensive device and yet one which will be exceedingly effective 60 for the purpose for which it is designed.

These objects we accomplish by means of such structure and relative arrangement of parts as will fully appear by a perusal of the following specification and claims.

In the drawings similar characters of reference indicate corresponding parts in the several views:

Fig. 1 is a fragmentary side elevation of the rotary unit showing the improved mounting 70 of the blades in connection therewith.

Fig. 2 is a front view of a standard end blade when the cutting edge of the blade is at its lowest position relative to the axis of rotation.

Fig. 3 is a similar view showing the parts 75 as viewed before the blade reaches said lowest position.

Fig. 4 is a top plan view of a blade and standard.

Fig. 5 is a fragmentary perspective view 80 of a standard showing a modified blade and mounting arrangement.

Referring now more particularly to the characters of reference on the drawings, and particularly at present to Figs. 1 to 4, the numeral 1 denotes the shaft of the rotary implement which shaft extends transversely of the line of travel. The numeral 2 denotes one of the discs mounted on the shaft to which radially projecting blade mounting 90 standards 3 are attached. Projecting forwardly from the outer ends of the standards relative to the direction of rotation of the unit are pads 4 on which the blades 5 are flatly supported and to which they are detachably secured by suitable means such as shown in our Patent No. 1,816,210, dated July 28, 1931.

The pads extend cross-wise of the standards or transversely of the implement and are 100

disposed at a forward angle to the standards slightly greater than 90° so that the forward edges of the pads with the rotation of the shaft follow a circular path of greater radius than the trailing edges of the pads. This positioning of the pads and consequently of the blades enables the latter to enter the ground with the desired chisel-like action.

Each individual blade of course projects 10 some distance in front of its pad and its cutting edge E, which is straight from end to end and which extends transversely of the implement, is disposed at an acute transverse angle to the line of travel. In this manner 15 the blade as it passes through the ground has an efficient shearing action on the roots etc. encountered thereby. One end A of the cutting edge is therefore advanced relative to the opposite end B, and if the pad is set on 20 the standard at right angles thereto in a horizontal transverse plane or parallel to the shaft, said advanced end of the blade will therefore engage the ground a greater distance from the axis of rotation than the opposite end B. As a consequence it will travel 25 in the ground through a circular path of greater radius and length than said opposite end B, with excessive wearing of the blade at the end A. To counteract this objectionable feature each pad is set on its standard at 30 an acute angle to a horizontal transverse plane as clearly shown in Fig. 3, so that the blade is disposed at a similar slope. The degree and direction of this transverse slope of 35 the pad and blade is such relative to the angle of the cutting edge that the radial distance D from the axis of rotation to both ends A and B of the blade is the same. The cutting 40 edge of the blade being straight from end to end said edge therefore lies horizontally in a circular path of the same radius.

The cutting edge of the blade throughout its length will therefore remain in the ground 45 for the same distance, insuring equal wear on the cutting edge at all points while at the same time the blade retains its angular setting and the desired shearing cutting action.

50 The same results are obtained with the arrangement shown in Fig. 5 wherein the pad 4a is set at a transverse right-angle to the pad or in a transverse horizontal plane parallel to the shaft. In this case the cutting edge 55 of the blade 5a is maintained so that both ends are the same distance from the axis of rotation as before by bending the blade in front of the pad and toward one side downwardly, as shown at 6, so that the cutting edge of the 60 blade is disposed on the same acute transverse angle to a transverse horizontal plane as if the pad itself were thus angled, as in the first described type.

From the foregoing description it will be 65 readily seen that we have produced such a de-

vice as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 70

Having thus described our invention what we claim as new and useful and desire to 75 secure by Letters Patent is:

1. In a rotary root cutting implement, a rotary member movable along the ground, and a blade mounted on such member substantially tangent to the axis thereof and adapted to rotate therewith; the blade having a straight cutting edge disposed at a transverse acute angle to the line of travel of the implement, and the body of the blade being set relative to the rotary member so that 80 both ends of such cutting edge are equidistant from the axis of rotation of such member. 85

2. In a rotary root chopping implement, a rotary member movable along the ground, a support extending radially of such member, 90 a pad mounted at the outer end of the support, and a blade fastened on the pad; the cutting edge of the blade from end to end being disposed at a transverse acute angle to the line of travel of the implement, and the pad being tilted at a transverse angle to the longitudinal plane of the support to such a degree relative to the angle of the cutting edge of the blade as to position both ends of such edge at points equidistant from the 95 axis of rotation of the rotary member. 100

In testimony whereof we affix our signatures.
